UNITED STATES PATENT OFFICE.

PAUL CRICCHIO, OF NEW YORK, N. Y., ASSIGNOR TO MAJESTIC LAMP WORKS, A PARTNERSHIP COMPOSED OF PHILIP SILBERHARTZ, JACOB SILBERHARTZ AND HARRY SCHEINER, ALL OF BROOKLYN, NEW YORK.

DESIGN FOR A LIGHTING FIXTURE BASE OR ARTICLE OF ANALOGOUS NATURE.

Application filed February 16, 1929. Serial No. 30,097. Term of patent 3½ years.

To all whom it may concern:

Be it known that I, PAUL CRICCHIO, a citizen of the United States, and a resident of New York, county of Bronx and State of New York, have invented a new, original, and ornamental Design for a Lighting Fixture Base or Article of Analogous Nature, of which the following is a specification, reference being had to the drawing forming a part thereof:

The single figure of the drawing shows a perspective view of the lighting fixture base or article of analogous nature.

I claim:

The ornamental design for a lighting fixture base or article of analogous nature substantially as shown.

PAUL CRICCHIO.
